S. C. HUFFMAN

BOX CLOSURE

Filed March 17, 1927

Inventor

S. C. HUFFMAN

By C. E. LANGE

Attorney

UNITED STATES PATENT OFFICE.

SAMUEL C. HUFFMAN, OF LINCOLN, NEBRASKA.

BOX CLOSURE.

Application filed March 17, 1927. Serial No. 176,117.

My invention relates to box closures and its object is the provision of a closure of extreme simplicity for automatically latching the lid when the lid is closed, the device being so constructed that it entirely covers the seam in the lid to exclude dust and vermin from the box and the latch being so constructed that it is easily operable when opening the box. A further object of my invention is to provide a closure which reinforces and strengthens the box.

Having in view these objects and others which will be pointed out in the following description, I will now refer to the drawings, in which

Figure 1 is a view in perspective of the box having my closure thereon.

Figure 2 is a fragmentary view in perspective showing one end of the closure and showing the latching members at one end of the box.

Figure 3 is a transverse sectional view through a portion of the lid of the box.

Figure 4 is a transverse sectional view through a portion of the box showing my latching device secured thereto and showing the lid in slightly spaced relation to the box.

Figure 5 is a view in perspective of a modified form of the latching device.

The box itself is preferably made from fiber board or carboard of suitable weight slitting and by folding the various parts together so as to form a box having a rectangular base. The lid is preferably formed by slitting the material of the box at the corners so as to provide two end flaps 10 and two side flaps 11^a and 11^b. In the closing of the box the end flaps 10 are first folded down and then the side flaps 11^a and 11^b are folded down in succession over the end flaps 10. Thus far the box is very effective for the storage of papers or other articles but an open seam is left between the inner edges of the side flaps 11^a and 11^b. Without a suitable latching device the side flaps 11^a and 11^b would tend to be forced up toward their open position. My closure and latching device are designed for completely closing the seam between the inner edges of the flaps 11^a and 11^b and for firmly latching these flaps in their closed positions.

The reinforcing strip at 12 for closing the seam between the flaps 11^a and 11^b is doubled upon itself at its outer edge with its inner edge portions spaced slightly so that it can

be fitted over the edge of the flap 11^b. It is secured to the flap 11^b by means of rivets 13 or the like and when it is thus secured, the edge portion of the flap 11^b is compressed as shown in Figure 3 so as to make the upper surface of the strip 12 continuous with the upper surface of the flap 11^b. The strip 12 is preferably made from any suitable sheet metal such as sheet steel of light gauge. Its free edge is offset as shown in Figure 3 so that it will fold down over the free edge of the flap 11^a in such a way that its upper surface will be practically continuous with the upper surface of the flap 11^a. By thus folding the strip 12 at its free edge I avoid all cut and rough edges which might cause trouble in the use of the box. The only cut edges in the strip 12 are embedded in the material of the flap 11^b.

The strip 12 is preferably made from a material which is more or less resilient. The end portions of the strip are bent downwardly and outwardly so as to form tongues 14 as best shown in Figure 4. These tongues have hooked ends which are directed outwardly and slightly upwardly. On the box itself and in line with the tongues 14 I secure resilient devices for engaging the hooks on the ends of the tongues 14. As best shown in Figure 4 the engaging device consists of a plate 15 of resilient metal which is doubled upon itself at its lower edge and which is secured to the box by means of rivets 16, the arrangement being such that the upper end portions of the engaging device are diverging. The inner member of the engaging device is slightly inturned at its upper edge so that the upper edge portion becomes embedded in the material of the box. The upper end portion of the outer member of the engaging device 15 is slotted at 16 so as to leave a catch 17 projecting inwardly and in the path of the hooked end on the tongue 14 when the flap 11^b is being closed. It is evident, of course, that the engaging device may be formed from two individual sheet metal members instead of one which is folded upon itself as shown in my drawings. The inner member of the engaging device is designed to prevent undue wear on the end of the box and it is obvious that when the box is formed from a material which will resist wear from abrasion, the inner member of the engaging device may be omitted altogether. In fact, the parts may be so adjusted that the tongue 14

will be out of all contact with the material at the end of the box, in which case the inner member of the engaging device may be omitted even when the box is made of cardboard.

5 It is obvious that the invention as described is susceptible of many variations and modifications. Merely by way of illustration I have shown one of these modified forms in Figure 5. In this instance the strap 12' is provided with depending ears 14' having outwardly projecting buttons 20. The engaging device 15' is similar to and almost identical with the engaging device 15, the only difference being that it is provided with 15 an aperture 16' instead of a slit. The aperture 16' lies in the path of the button 20 and its size is such that it will engage the button 20 when the lid of the box is closed. In this case also the latch may be released by disengaging the member 15' from the button 20.

Having thus described my invention in such full, clear, and exact terms that its construction and operation will be readily understood by others skilled in the art to which it

pertains, what I claim as new and desire to 25 secure by Letters Patent of the United States is:

In combination, a box having a two-part lid for closing the entire top side of the box except for a narrow slit at the meeting edges 30 of the parts of the lid, a strap secured to one part of the lid so as to project over the other of the parts of the lid to thereby cover the narrow slit between the meeting edges of the parts of the lid, members depending from 35 said strap at the outer extremities thereof, said members being outturned at their lower extremities, and resilient members secured to said box and having their upper edge portions spaced from the walls of said box, said 40 resilient members being provided with narrow inwardly projecting lips for engaging the outturned portions of said depending members on said strap when said lid is moved to closing position.

45 In testimony whereof I affix my signature.

SAMUEL C. HUFFMAN.
